2 SHEETS-SHEET 2.

UNITED STATES PATENT OFFICE.

STEPHEN JAROSS, OF PHILADELPHIA, PENNSYLVANIA.

DEVICE FOR DELIVERING AND RECEIVING MAIL-BAGS FROM TRAINS AND THE LIKE.

No. 921,254.

Specification of Letters Patent.

Patented May 11, 1909.

Application filed February 13, 1908. Serial No. 415,635.

To all whom it may concern:

Be it known that I, STEPHEN JAROSS, a subject of the Emperor of Austria-Hungary, residing in the city and county of Philadelphia, State of Pennsylvania, have invented a new and useful Device for Delivering and Receiving Mail-Bags from Trains and the Like, of which the following is a specification.

10 My invention relates to a new and useful mail bag receiver and deliverer and consists of a suitable deliverer or supporting device carried by the car from which the bag is removed and means carried by the car for receiving a mail bag.

It further consists of novel means for locking and unlocking the bag upon the deliverer.

It further consists of a novel device for removing the bag from the deliverer.

20 It further consists of other novel details of construction, all as will be hereinafter set forth.

Figure 1 represents a side elevation of a mail bag receiver and deliverer embodying my invention, showing a portion of a car and showing, in dotted lines, the position of the receiver in the act of receiving a mail bag. Fig. 2 represents a plan view of a portion of the device for swinging in the receiver and 25 deliverer, in detached position. Fig. 3 represents a partial plan view and partial sectional view of a portion of the car showing the receiver and deliverer in position. Fig. 4 represents a plan view of the means for receiving the mail bag from the car and for delivering another thereto. Fig. 5 represents 30 an end elevation of the device showing the operation of the catch. Fig. 6 represents a perspective view of the mail bag clamp. Fig. 7 represents a portion of the device 35 showing the catch in a different position from that shown in Fig. 5. Fig. 8 represents a sectional view of a portion of the receiving means and a portion of the clamp. Fig. 9 represents in elevation, a portion of the car 40 showing a different means for pivoting the receiving and delivering apparatus.

Similar numerals of reference indicate corresponding parts in the figures.

50 Referring to the drawings. I have found in practice that in mail delivering and receiving apparatus, it is necessary to suitably support the mail bag from the car and to provide means for receiving the same therefrom and in constructions now in use where the mail bag itself is grasped, owing to the

speed in which a train is running, that the impact will often injure the mail bag and in some instances entirely destroy the same, thus injuring the mail itself, in many instances. In the present instance I have shown a construction for overcoming these difficulties and for carrying out my invention, but it will be evident that the arrangement of the parts may be varied and other instrumentalities may be employed which will come within the scope of my invention.

1 designates a portion of a car having the usual opening comprising the door. Pivotally supported upon the car at a suitable point with respect to the door thereof, is a frame or support 2 which may be of any desired construction and which carries a pin or hook 3. Pivotally supported upon the support 2 is a catch or lock 4 against which bears a spring 5 adapted to normally hold said catch or lock at a suitable point or position above the hook 3. Connected with or forming part of the lock 4 is an arm 6 for purposes to be hereinafter explained. Projecting forwardly from the support 2 and at a suitable point thereon is a pin 7 which is preferably slightly depressed at 8 to form a seat for the mail bag clamp.

9 designates a latch suitably carried by an arm 10 and so placed with respect to the pin 7 that when the clamp which carries the mail bag strikes the same, the said latch permits the passage of the clamp after which said latch falls to the position seen in Fig. 1, and prevents the escape of the clamp, and mail bag carried thereby, from being released from the seat 8, said latch 9 being provided with a suitable stop to prevent 95 improper outward movement thereof.

Suitably supported at the station or other place, at which it is desired to deliver and receive mail, are the tracks or guides 11, which, in the present instance, are supported on the uprights 12 and which are inclined 100 as best seen in Fig. 1 and the ends of said tracks, at which the mail bag and clamp will first pass are inclined outwardly as at 13, as seen in Fig. 4, in order to provide that the mail bag supporting clamp will be positively directed to the proper position with respect to the tracks or guides 11. Leading downwardly from the other end of said tracks or guides, if desired, I provide the inclined or curved tracks 14 suitably supported and having cut-away portions as at 15 for the ease of removal of the clamp as will

be hereinafter described. In line with the guides 11 are the bars 16 upon which is adapted to be supported, a mail bag clamp carrying the mail bag which is to be delivered to the car.

17 designates the mail bag clamp which is provided with the lugs 18 forming seats 19 on opposite sides of the body of the clamp and secured to or integral with the body, is 10 the eye 20. Carried by the lower portion of the clamp is a bar 21 having a recess 22 therein, while hinged or otherwise secured to the said bar 21 is the bar 23 which can be connected and disconnected from the bar 21 by 15 any suitable means, in the present instance, by the screws 24 carrying thumb nuts 25.

26 designates an opening in the body of the clamp which is adapted to receive the pin 7.

20 The operation of the device is as follows:— The bar 23 is released from engagement with the bar 21 and the end of the mail bag 27 is placed therebetween and the bars are suitably reconnected, by manipulation of the 25 thumb nuts 25. The support 2 on the car having been swung inwardly, the operator places the hook or pin 3 in the eye 20 of the support, it being understood that in order to place the pin or hook 3 within the eye 20 that 30 it is necessary to move over the lock or catch 4 against the tension of the spring 5 and that after the eye 20 is in proper position, and the catch 4 released, it will be situated directly over the eye 20, as seen in Fig. 1 and will prevent the accidental escape of the clamp from 35 the support. The support is now swung outwardly into the position seen in Figs. 1 and 3, and in order to properly hold the same in this position, I may desire to provide the 40 pivot arms 28 and 29, one end of which is connected or supported and the other end of which is suitably supported so that when the arms are in the position seen in Fig. 3, the support will be suitably held as the car advances forwardly in the direction indicated 45 by the arrow in Fig. 3. It will be seen that the said clamps are substantially in line to pass between the guides 11. As the car continues moving forwardly, the clamp and its 50 support will pass between the guides and the arm 6 on the lock 4 will contact with one of the guides 11, which will actuate the catch 4 and move the same into the position seen in Fig. 5, so that the catch 4 is removed from a 55 position above the eye 20. In the meantime, as the car continues its forward movement, the lugs 18 will be situated upon the outer side of the guides 11, so that the latter will finally be situated in the seats 19. As the 60 guides 11 are upon an incline, they will gradually raise the clamp 17, remove the eye 20 from engagement with the hook or pin 3 and the clamp 17 carrying the mail bag 27, will be released from the support 2 and will remain 65 upon the guides 11, or by reason of the mo-

mentum when released will be directed downwardly on the tracks 14 and will strike the ground or be directed into a suitable receptacle. The cut away portion 15 of the tracks permits easy removal of the clamp 17 from the 70 track. In this manner the mail bag is delivered from the car. In the meantime, the operator at the station has connected another bag as 30 with a suitable clamp 17 and has hung the same upon the bars 16. As the 75 train continues to advance the pin 7 will be in a suitable plane to enter the opening 26 in this clamp 17, this position being understood from Figs. 1 and 7, and the upper portion of the clamp forces back the latch 9 into the 80 position seen in dotted lines, Fig. 1, until the clamp has passed the latch which will then be lowered into the position seen in full lines, Fig. 1, will be seated in the seat 8 and carried along with the train, after which the support 85 2 can be swung in, carrying with it the bag 30 which is thus delivered to the car. In order to swing in the support 2, I may provide any suitable means and in Fig. 2, I have shown one form which consists of the links 31 and 90 32 connected with a lever 33 which by suitable manipulation will swing the support 2. I may connect the support 2 in any suitable manner with the car and in Fig. 9, I have shown another form from that shown in the other 95 figures, which consists in providing journals 34 and 35 on the car, the operation of the parts being the same as hereinbefore described.

From the above it will be seen that the 100 mail bag itself does not come in contact with any portion of the device, that the clamp 17 can be quickly and expeditiously connected with the bag and that the delivering device can be easily hung upon the bar 16 for the receiver.

It is to be noted that means are employed to maintain the frame or support 2 in its opened or closed position and in Fig. 2, I have shown one mechanical construction 110 which will accomplish this result. Referring to said Fig. 2, it will be seen that a spring 36 is employed, which is provided with the lugs or equivalent devices 37 and 38, which are adapted to co-act with the lever 31 to lock 115 the same in either its opened or closed position, so that the device cannot be accidentally moved due to the vibration of the car or other causes after it is once set in the desired position.

Having thus described my invention, what I claim as new and desire to secure by Letters Patent, is:—

1. In a device of the character described, a suitable support, a pin thereon, a clamp 125 adapted to be connected with the mail bag, means for carrying said clamp upon said support and means for elevating said clamp, whereby the same is released.

2. In a device of the character described,

a suitable support, a clamp adapted to be attached to a mail bag, means for supporting said clamp upon said support, means for locking said clamp in position on said support and means for actuating said locking means, whereby the clamp can be removed.

3. In a device of the character described, a support, a clamp adapted to be connected with a mail bag, means for connecting said support with said clamp, and a spring lock for normally holding said clamp in position on said support and means for actuating said lock to release said clamp and for elevating said clamp, whereby it is removed from said support.

4. In a device of the character described, a support, a pin thereon, a clamp adapted to be connected with a mail bag, an eye on said clamp in which said pin is adapted to be seated, a spring actuated catch carried by said support for locking said eye on said pin, an arm on said catch, and a guide suitably supported to actuate said arm to release said catch, whereby the clamp with the mail bag can be removed from the support.

5. In a device of the character described, a support, a clamp with which a mail bag is adapted to be connected, means for supporting said clamp on said support, a catch for locking said clamp on said support, and guides for releasing said catch and for removing said clamp from said support.

6. In a device of the character described, a support, a clamp with which a mail bag is adapted to be connected, means for supporting said clamp on said support, a catch for locking said clamp on said support, and guides situated at an incline for releasing said catch and for removing said clamp.

40 7. In a device of the character described, a support, a pin projecting forwardly therefrom, a clamp with which the mail bag is adapted to be connected, said clamp having an opening therein adapted to receive said pin and means passing said clamp and preventing accidental displacement of the same from said pin.

8. In a device of the character described, a support, a pin projecting therefrom, a latch suitably situated with respect to said pin, and a clamp adapted to be connected with a mail bag and having an opening for the reception of said pin, said latch passing said clamp and preventing accidental displacement of said clamp therefrom.

9. In a device of the character described, a support, a clamp with which a mail bag is adapted to be connected, means for supporting said clamp on said support, a catch for locking said clamp thereon, guides situated at an incline adapted to actuate said catch to release said clamp and to elevate the said clamp to release the same from the support, and outwardly turned ends to said guides.

10. In a device of the character described, a support, a clamp with which a mail bag is adapted to be connected, means for supporting said clamp on said support, a catch for locking said clamp thereon, guides situated at an incline adapted to actuate said catch to release said clamp and to elevate the said clamp to release the same from the support, and downwardly curved tracks leading from said guides. 70 75

11. In a device of the character described, a clamp having lugs thereon forming seats, and means on said clamp for engagement with a mail bag.

12. In a device of the character described, a clamp, having an opening therein, an eye carried by said clamp, lugs on said clamp forming seats and means on said clamp for engagement with a mail bag. 80

13. In a device of the character described, a support, an upwardly extending hook thereon, a catch adjacent said hook, and a forwardly projecting pin on said support. 85

14. In a device of the character described, a support, an upwardly extending hook thereon, a catch adjacent said hook, a forwardly projecting pin on said support, and a latch for holding a mail bag on said forwardly projecting pin. 90

15. In a device of the character described, a support, a clamp with which a mail bag is adapted to be connected, means for supporting said clamp on said support, means for locking said clamp on said support, and means for releasing said locking means and for removing said clamp from said support. 95 100

16. In a device of the kind described, the combination with a stationary mail bag support adapted to be located alongside a railroad track and a movable bag support adapted to be secured to a car, of a pendent member upon the movable bag support adapted to sustain a mail bag, and means upon the stationary support operative through movement of the movable member to lift the aforesaid pendent member clear of the movable member. 105 110

17. In a device of the kind described, the combination with a stationary mail bag support adapted to be located alongside a railroad track and a movable bag support adapted to be secured to a car, of a pendent member upon the movable bag support adapted to sustain a mail bag, means upon the stationary support operative through movement of the movable member to lift the aforesaid pendent member clear of the movable member, and means upon the stationary support for sustaining said pendent member after it is released from the movable member. 115 120 125

18. In apparatus of the kind described, the combination with a stationary mail bag support adapted to be located alongside a railroad track and a movable bag support upon a car, of a bag supporting rider upon 130

the movable member, and guide arms adapted to receive the rider upon the stationary support.

19. In apparatus of the kind described, the combination with a stationary mail bag support adapted to be located alongside a railroad track and a movable bag support upon a car, of a bag supporting rider upon the movable member, guide arms adapted to receive the rider upon the stationary support, and inclined sections upon the guide arms adapted to engage and lift the rider clear of the movable member.

20. In a device of the kind described, the combination with a stationary bag support provided with guide arms and lifting sections thereon, of a movable bag support provided with a loop and a bag supporting rider in the loop, the rider being adapted to coöperate with the guide arms of the stationary bag support, substantially in the manner and for the purpose specified.

STEPHEN JAROSS.
